COMBINED CLOSURE CAP AND CARRYING HANDLE FOR A BOTTLE OR THE LIKE

Morton B. Stull, Boonton, N.J. (© Stull Engraving Company, 221-223 Banta Ave., Garfield, N.J.)

Filed June 16, 1965, Ser. No. 85,758

Term of patent 14 years

(Cl. D58—26)

Fig. 1

Fig. 4

Fig. 2

Fig. 5

FIGURE 1 is a side elevational view of a combined closure cap and carrying handle for a bottle or the like, showing my new design.

I claim:

The ornamental design for a combined closure cap and carrying handle for a bottle or the like, as shown.
